(57) **CLAIM**

The ornamental design for a stroller cup holder, as shown, and described.

DESCRIPTION

FIG. 1 is a perspective view of the stroller cup holder;
FIG. 2 is a front side view of the stroller cup holder;
FIG. 3 is a rear side view of the stroller cup holder;
FIG. 4 is a right side view of the stroller cup holder;
FIG. 5 is a left side view of the stroller cup holder;
FIG. 6 is a bottom view of the stroller cup holder; and,
FIG. 7 is a top view of the stroller cup holder.

The broken line showing is included for the purpose of illustrating unclaimed subject matter and forms no part of the claimed design.
